UNITED STATES PATENT OFFICE

2,254,873

FASTENING DEVICE

Eugen Prestinari, Summit, N. J., assignor to
Gemex Company, Newark, N. J., a corporation
of New Jersey

Application February 3, 1940, Serial No. 317,140

7 Claims. (Cl. 24—241)

This invention relates to a fastening device and more particularly to a fastening device to be used with bracelets or necklaces.

One of the objects of this invention is to provide a simple, inexpensive, and practical fastening device well adapted to meet varying conditions of use. Another object is to provide a fastening device of the above character which is neat and attractive in appearance and is of such sturdy construction as to withstand hard usage. Another object is to provide a fastening device of the above character which is inexpensive to manufacture and easy to assemble. Another object is to provide a fastening device of the above character which may be manufactured from light and inexpensive materials. Another object is to provide a fastening device of the above character in which the connection can be quickly made by the user with a minimum of effort. Other objects will in part be obvious and in part pointed out hereinafter.

This invention, accordingly, consists in the features of construction, combinations of elements, and arrangements of parts, as will be exemplified in the structure to be hereinafter described and the scope of the application of which will be indicated in the following claims.

In the accompanying drawing in which is shown one of the various possible embodiments of my invention:

Figure 1 is a perspective view of my fastening device secured to the end link of a bracelet;

Figure 2 is a side elevation of the construction shown in Figure 1;

Figure 3 is an enlarged top plan view of the fastening device shown in Figures 1 and 2 with the cover member in an open position;

Figure 4 is a sectional plan view taken along the line 4—4 of Figure 2; and

Figure 5 is a sectional elevation taken along the line 5—5 of Figure 4.

In order that the various novel features of my invention may be more readily understood, it might here be pointed out that when a bracelet or necklace is placed upon the arm or neck, the bracelet or necklace clasp is usually so small that difficulty is experienced in making the connection. More particularly in devices in which the bracelet end link is hooked to a clasp before the catch is operated, the end link often works out of the clasp before the catch can be closed, or the link twists sideways. When the coupling of the link twists sideways, it jams the cover member as it is rotated toward a closed position. Furthermore, forcing the cover towards its closed

position when the link is clogged damages the clasp. Still further difficulties arise upon operation of clasps of this nature by reason of the user's inability to securely grasp the operating parts because of the smallness thereof. It is, accordingly, another object of this invention to provide a fastening device which will effectively overcome these difficulties.

Referring now to the drawing, the fastening device comprises a body member, generally indicated at 10 (Figure 2), having a cover member, generally indicated at 11, pivotally mounted thereon. A pair of slots 12 are formed in one end of body member 10 and are adapted to receive the coupling 13 (Figures 1 and 5) of the connecting link 14. A wedge-shaped catch (Figures 3, 4, and 5), generally indicated at 15, is mounted in body member 10 and yieldingly projects into slots 12. Link 100 is secured to the other end of body member 10 in any suitable manner such as by soldering. When the device is in use, coupling 13 of link 14 is pressed down in slots 12 and snaps past catch 15. This catch holds the link and body member in the proper relationship while the user is rotating cover member 11 to lock the link and the fastening device together.

The body member is preferably oval in shape (Figure 4) and comprises a bottom 16 (Figure 5), end walls 17 and 18 (Figure 4), side walls 19 and 20, and top 21 (Figures 3 and 5). The bottom and walls are preferably stamped from a single piece of metal. Top 21 extends between side walls 19 and 20, preferably having its top surface flush with the upper edges of the side walls (Figure 5). A flange 80 (Figures 4 and 5) extends downwardly from the top 21 to bottom 16 adjacent end wall 17, and two flanges 23 and 24 (Figure 4) extend downwardly to the bottom at the opposite end of top 21. Tongue 25 (Figures 3 and 5), which is an integral part of top 21, extends outwardly therefrom between flanges 23 and 24, projecting toward slots 12 for purposes set forth below.

Slots 12 are cut in side walls 19 and 20 between flanges 23 and 24 and end wall 18, and extend downwardly therethrough substantially to bottom 16 (Figure 5). At the bottom of the slots, a pair of notches 12a are preferably cut in side walls 19 and 20 to receive coupling 13 of end link 14. These notches help prevent upward movement of coupling 13 after it has been placed in slots 12 as the natural tendency of a bracelet or necklace is to pull apart, which, acting in

conjunction with catch 15, holds coupling 13 within the notches.

Referring now to Figures 4 and 5, a shaft, generally indicated at 70, is secured to cover member 11, and comprises a main portion 26 and a reduced portion 27. Reduced portion 27 extends through a hole 71 formed in bottom 16 and has its outer end riveted over a washer 29. The main portion of the shaft is non-circular in shape, and preferably square, and its lower end abuts against bottom 16. Thus, shaft 70 pivotally mounts cover 11 on body member 10.

As best shown in Figures 4 and 5, a U-shaped spring, generally indicated at 30, extends between flange 80 and flanges 23 and 24. Spring 30 is preferably flat and positioned between top 21 and bottom 16, and the inner sides of its legs 31 and 32 abut against main portion 26 of shaft 70. Thus, as the cover member is rotated, shaft 26 spreads the legs of the spring as shown by the outlined positions in Figure 4, and whenever the cover member is rotated beyond a balance point—namely, when the square shaft is diagonally between the legs of the spring, the cover member snaps into an open or closed position.

Wedge-shaped catch member 15 has a reduced shank 33 which extends into the central portion of the body member through the slot 34 (Figure 4) between flanges 23 and 24, and terminates in an enlarged plate 35. The outer surface of plate 35 abuts against the inner surfaces of flanges 23 and 24. Preferably a space is provided between shank 33 and the edges of slot 34 permitting catch member 15 limited movement in a sidewise direction. A spring 36 (Figure 4) presses the inner side of plate 35 yieldingly holding against the inner side of plate 35 yieldingly holding the wedge-shaped portion of catch member 15 between slots 12. The inner end of the spring preferably lies in a cup-shaped member 37 (Figures 4 and 5) which prevents shaft 70 from interfering with springs 36 when the shaft is rotating.

In operation, the cover 11, which forms the secondary catch, is turned to an open position as shown in Figure 3, and coupling 13 is slid downwardly into slots 12 (Figure 5). Coupling 13 strikes the top surface 38 (Figure 5) of primary catch 15 which forces primary catch 15 inwardly toward shaft 70, permitting coupling 13 to snap past the catch and enter notches 12a (Figures 2 and 5). When coupling 13 has passed catch 15, spring 36 forces the catch outwardly so that it again closes the slot. Catch 15 retains coupling 13 within the slots as cover 11 is rotated and prevents portion 13 from jumping out of slots 12. It should further be noted that when coupling 13 is moving downwardly in slots 12 it forces the wedge-shaped portion of catch 15 downwardly, increasing the angle of surface 38 which permits coupling 13 to be slid easily past catch 15.

As noted above, catches of this nature are subject to jamming and damage by reason of the coupling being placed in the slots askew. Thus, when the coupling has one end diagonally crosswise of the slot, the cover member strikes it resulting in damage thereto. Also, a person trying to close a cover when the coupling is in this position would damage the slots. This is prevented by having primary and secondary catches. The primary catch retains the coupling within the slot preventing it from jumping out of or twisting in the slot while the secondary catch is being operated, and the secondary catch firmly locks the coupling to the body member.

When it is desired to disconnect link 14 and body member 10, the cover 11 is turned to the position shown in Figure 3 and the user lifts upwardly upon link 14. Coupling 13 strikes surface 39 of catch 15, tilting it upwardly until it strikes tongue 25 (Figure 5). This increases the angle of surface 39, permitting coupling 13 to be snapped past catch 15.

Cover 11 is oval in shape and has a flat top 55 (Figures 1 and 3). The longitudinal edges of the cover are beveled to form points 42, 43, 44, and 45 with top 55 at the ends of the cover. Thus, when the user twists cover 11, he gets a secure grip on it because of its beveled edges and, as he twists, his fingers strike the points on the ends thereof which greatly facilitates operation of the cover.

Thus, my fastening device has primary and secondary catches, one of which forms a temporary catch to hold the link and catch in interlocked relationship while the secondary catch is being operated, and furthermore the device has a cover so designed that it may be easily rotated by the user. It will now become clear that I have provided a thoroughly practical and durable fastening device in which the several objects hereinabove mentioned, as well as many others, are accomplished.

As many possible embodiments may be made of the above invention and as many changes might be made in the embodiment above set forth, it is to be understood that all matter hereinabove set forth or shown in the accompanying drawing, is to be interpreted as illustrative and not in a limiting sense.

I claim:

1. In an article of the nature described, in combination, a body member having an opening therein, wedge-shaped catch means projecting into said opening, the wedge-shaped surfaces of said catch facing the open and closed ends of said slot, a coupling adapted to be moved into and out of said opening, spring means resiliently pressing said wedge-shaped catch into said opening, whereby when said coupling is inserted into or removed from said opening it coacts with one or the other of the surfaces of said catch means permitting said coupling to pass said catch means in said opening, and secondary catch means for closing the open end of said opening.

2. In an article of the nature described, in combination, a body member having a slot therein, a wedge-shaped catch loosely mounted on said body member and projecting into said slot, spring means resiliently urging said catch into said slot, a link member adapted to be inserted into said slot, whereby when said link member is inserted into said slot said wedge-shaped member tilts as said link is pressed against it increasing the angle of the surface abutting the link, whereby said link portion may be snapped into and out of a locked position on said body member, and secondary catch means mounted on said body member adapted to close the open end of said slot after said link is yieldingly retained therein by said first-mentioned catch.

3. In a fastening device adapted to connect the ends of a bracelet or a necklace or the like, in combination, a body member having a vertical slot therein, a coupling adapted to be inserted into said slot to connect the opposite ends of a bracelet, a cover member pivotally mounted on a vertical axis on said body member for closing and opening movement thereof relative to said slot, a supplemental catch on the body operable between

open and closed positions with respect to said slot and adapted to yieldingly hold said coupling therein, whereby when said coupling is inserted into said slot, it is held therein by said supplemental catch out of the path of said cover, whereby jamming of said cover against said coupling is precluded.

4. In a fastening device adapted to connect the ends of a bracelet or a necklace or the like, in combination, a body member having a slot formed therein, a notch cut in said slot at the bottom thereof extending toward the adjacent end of said body member, a coupling adapted to be inserted into said slot to connect the opposite ends of a bracelet, catch means mounted on said body member extending into said slot, whereby, when said coupling is inserted into said slot and pressed past said catch, it is resiliently held within said notch by said catch, and a cover member connected to said body member for closing and opening movement thereof relative to said slot.

5. In a device of the nature described, in combination, a link member, a body member having a slot therein, a wedge-shaped catch member projecting into said slot, resilient means normally yieldingly holding said catch member in said slot, the wedge-shaped surfaces of said catch member facing the open and closed ends of said slot, said catch member being operated by said link member as said link member is pressed into or removed from said slot, and a second catch member pivotally mounted on an axis vertical to said body member, said second catch member being

adapted to be pivoted on its axis to close the open end of said slot.

6. In a fastening device adapted to connect the ends of a bracelet or the like, in combination, a bracelet, a body member connected to one end of said bracelet having an opening formed therein, a coupling connected to the other end of said bracelet adapted to be inserted into said opening, primary catch means resiliently mounted on said body member normally adapted to yieldingly close said opening, said primary catch means being operated by said coupling as said coupling is inserted into or removed from said slot, and secondary catch means operatively connected to said body member for closing said opening after said coupling has been inserted therein.

7. In an article of the nature described, in combination, a body member having a slot therein, a link member, a portion of said link member being adapted to fit in said slot, primary catch means resiliently mounted on said body member and yieldingly closing said slot, said primary catch means being operated by said link member as said link member is inserted into or removed from said slot, and a member pivotally mounted on an axis vertical to said body member and operable independently of said catch means, said pivotally mounted member being adapted to be pivoted into a closed position to close the open end of said slot, whereby a portion of said link member may be locked therein.

EUGEN PRESTINARI.
